DISPENSING DEVICE

Daniel Topjian, Watertown, Mass., assignor, by
mesne assignments, to himself, as trustee

Application October 15, 1942, Serial No. 462,199

17 Claims. (Cl. 206—30)

This invention concerns dispensing apparatus and relates more particularly to means for dispensing matches, although in its broader aspects it is contemplated to have other utilities. Customarily, matches are sold either loose, in cardboard or thin wood-veneer boxes containing a substantial number of matches (said boxes being of a wholly utilitarian character and of unaesthetic appearance) or in packages containing relatively few matches, but which like the boxes make no pretension to artistry in form or surface finish. Furthermore, both types of container are usually of inflammable material such that if the matches are accidentally ignited, the entire container may be consumed to the great damage to surrounding objects. Moreover, whether the container be a box or packet, the person desiring a match must ordinarily employ both hands in securing a match from the closed container.

One object of the present invention is to provide a dispensing container for matches which, if desired, may be of highly ornamental and aesthetic appearance; which may be made, if desired, of a substantially fireproof or fire-resistant material such that if by chance the matches within it should become ignited it would protect its surroundings from fire damage; and to provide a dispensing receptacle from which individual matches may be withdrawn by the use of one hand only.

In my prior Patent No. 2,139,050 I have enumerated certain of the advantages to be gained by impregnating, coating or otherwise treating a match so that when burned it emits a pleasing fragrance rather than the disagreeable odor ordinarily resulting from the burning or smoldering of the match stick and the chemicals forming its tip. As described in said patent, such a desirable fragrance was conditional upon the treatment of the match during manufacture. However, it is not always possible to obtain matches treated in accordance with the disclosure of my prior patent, and a further object of the present invention is to provide means whereby an article to be dispensed, for instance a match, may become automatically perfumed while within the dispensing container awaiting dispensing, thereby making it possible to obtain the benefits of the perfumed article, though the article when placed in the dispensing container may be of the common, that is to say, unperfumed type.

A further object of the invention is to provide a dispensing container comprising a holding means in which a match may be arranged, ta-

per-like, so as to be burned solely for the purpose of perfuming the surroundings and without danger that the burning match will cause damage either from its flame or from its incandescent ash.

Other and further objects and advantages of the invention will be pointed out hereinafter in the following more detailed description, and by reference to the accompanying drawing, wherein

Fig. 1 is a side elevation of one desirable embodiment of dispensing receptacle or container in accordance with the present invention;

Fig. 2 is a vertical diametrical section through the container of Fig. 1;

Fig. 3 is a horizontal section, substantially on the line 3—3 of Fig. 2;

Fig. 4 is a plan view of a removable holder applicable to the container of Fig. 1, for holding matches while being burned;

Fig. 5 is a diametrical section of the holder of Fig. 4; and

Fig. 6 is a diagrammatic side elevation showing the holder assembled with the receptacle or container of Fig. 1.

Referring to the drawing, the numeral 1 designates a dispensing receptacle particularly designed for dispensing matches. This receptacle comprises a base including an annular horizontal flange portion 2 designed to rest upon a suitable support, for example the top of a table, and the upwardly directed hollow circular boss 3 having the horizontal top wall 4. This boss defines a chamber 5 within the base.

The top wall 4 of the boss is furnished with a central bearing opening for a short vertical shaft 7 to whose lower end is secured a ratchet wheel or disk 8. A spring pawl or detent 9 engages the teeth of this ratchet disk and thus prevents free rotation of the shaft although allowing the shaft to be turned step by step in the proper direction by the application of sufficient force. To the upper end of the shaft, just above the top wall 4 of the boss, is secured a spool support 10, here shown as a disk provided with one or more upstanding eccentrically located projecting connecting pins or lugs 11.

The dispensing receptacle, as here illustrated, also comprises a substantially cylindrical shell 12 which may be of sheet metal, molded plastic, or the like, but which preferably, like the rest of the receptacle, is of a non-inflammable or at least fire-resistant material. The lower end of this shell 12 is telescoped over the boss 3 and is permanently fixed to the base in any desired manner, for example by rivets or welding. A

cover 13 normally closes the upper end of the shell 12. This cover is furnished with a downwardly directed marginal flange 14 which embraces the upper end of the shell, but which fits about it with sufficient clearance to permit relative rotation of the cover and shell. For convenience in rotating the cover, the latter may be provided with a central upstanding knob or handle 15.

Projecting down from the center of the cover is a boss 16 to whose lower end is secured a drive element 17, here shown as a disk having one or more downwardly directed eccentrically located driving pins or lugs 18.

The receptacle as thus described is designed to receive a spool which supports a roll R of connected articles which are to be dispensed, such articles here being shown as the matches M. These matches are arranged in series and are connected only at points adjacent the lower ends of the match sticks, the latter being for example of paper or cardboard such as is commonly used in making matches which are sold in packet form.

The spool on which the roll R of matches is mounted, is here illustrated as comprising a tubular barrel 19 having heads 20 and 21 rigidly secured to its lower and upper ends respectively. The head 20 is here shown as imperforate, but the upper end 21 is annular so as to provide access to the interior of the barrel. As here shown, this barrel is made of rigid material provided with perforations 22 for example, perforated metal, but it is contemplated that the barrel may be made of any desired construction, so long as it is pervious to the radial passage of volatile substances.

Preferably, an annular shelf 23 is mounted on the barrel 19, such shelf being adjustable axially of the barrel if desired and constituting a support for the lower end of the roll R of matches.

The shell 12 is provided with an elongate dispensing slot 24, one margin of which, as shown at 25 in Fig. 3, is bent inwardly to form a deflector or guide operative to engage the inner face of the outer convolution of the row of matches and to guide the endmost match outwardly through the slot. The opposite edge 26 of this slot may if desired be sharp or provided with small serrations and is designed to assist in tearing off the endmost match when the latter has been projected outwardly through the slot.

Within the hollow barrel 19 of the spool is a body 27 of absorbent material, for example cotton batting or paper fibre, and this body of material contains a volatile substance of such a character that as it gradually evaporates it passes out through the pervious material of the barrel 19 and into the surrounding roll R of matches thereby imparting to the matches a pleasing fragrance or at least the capability of emitting a pleasing odor when they are burned. Thus, although the ribbon of matches forming the roll R may initially be of ordinary type, the roll of matches automatically acquires a pleasing fragrance when arranged within the dispensing receptacle so that when removed and burned the matches have substantially the same characteristics as those described in my above-named patent.

To assist in using matches as perfumed-emitting tapers, the receptacle may be provided with the holder 28 (Figs. 4 and 5) such holder preferably being of sheet metal or other non-inflammable material and having a central aperture 29 so that the holder may be slipped down over the knob 15 and rest upon the cover 13 of the recep-

tacle. Surrounding the aperture 29 is a series of sockets 30, each of a size to receive the end of a match stick and to hold the match M in upright position while it is burning. Preferably, immediately surrounding the series of sockets 30 is a trough-like channel 31 designed to receive the ashes which may drop from the match as it burns. This holder may be mounted on the top of the dispensing receptacle (Fig. 6) and matches torn off from the roll R may be set in the sockets 30 and ignited and as they burn such matches will emit a pleasing fragrance. While so burning the matches are properly supported and any ashes which may fall are collected in the trough 31 and thus there is no danger of damage to the surroundings by such use of the matches. Furthermore since the entire receptacle forms a substantially fireproof housing there is little danger of damage to surroundings even though through an accident the matches forming the roll R should become ignited. Since the receptacle has a very firm base and since the matches are presented one-by-one at the slot 24, the user may readily tear off a match by the use of one hand only.

Spools with the rolls of matches mounted thereon may be supplied as refills for the dispensing receptacle, or on the other hand, the spool may be regarded as a permanent part of the receptacle and the ribbons of connecting matches may be wound upon the barrel of the spool by the user preparatory to dispensing. The natural resiliency of the ribbon of matches tends to cause the roll to expand in diameter and thus the outer convolution tends to engage the inner surface of the shell 12. Since the drive pins 18 enter openings in the upper head 21 of the spool while the openings in the lower head 20 receive the connecting pins 11 projecting up from disk 16, the rotation of the knob 15 turns the spool against the opposition of detent 9. When the knob 15 is turned the endmost match is caused to approach and to emerge through the slot 24 being guided outwardly by member 25 into a position such that it may readily be grasped and torn off from the ribbon of connected matches. The remaining matches are confined within the receptacle until another match is required, when the spool may be advanced another step. If desired the teeth on the ratchet wheel 8 may be so spaced that the spool will turn through a distance just sufficient to deliver a single match each time that the detent 9 springs from one tooth to the next. However, this is not an essential feature, the detent and ratchet being principally employed to make sure that the spool will not rotate in the reverse direction and to prevent excess movement of the spool when it is turned for delivering matches.

While the part 2 has been referred to as a "base" and the part 13 as a "cover" and the shaft has been referred to as a "vertical" and while the terms "upper" and "lower" have been employed, it is to be understood that such words are used merely for convenience in description with reference to the apparatus as illustrated, and are not to be regarded as limiting or as indicating that the apparatus may not be used in some other position than that illustrated.

While one desirable embodiment of the invention is here illustrated by way of example it is to be understood that the invention is not necessarily limited to this precise embodiment but is to be regarded as broadly inclusive of any and all

equivalents falling within the terms of the appended claims.

I claim:

1. A dispensing receptacle comprising an elongate hollow core for the reception of a roll of connected articles to be dispensed, said core being pervious, a body of absorbent material within the core designed to hold a volatile odoriferous substance capable of escaping through the pervious core and of imparting its characteristic odor to the roll of connected articles mounted on the core, means normally closing the ends of the core, means supporting the core for rotation thereby to permit the roll of attached articles gradually to be unwound from the core as individual articles are dispensed, and means operative to facilitate the detachment of said articles as they are unwound from the roll.

2. In combination in a dispensing receptacle, a spool having a hollow elongate barrel and a head at each end of the barrel, the barrel having openings in its wall, one of the heads having a central aperture giving access to the interior of the barrel, a body of absorbent material within the barrel operative to hold a volatile odoriferous substance in such relation to a roll of connected dispensable articles wound on the barrel as to impart the characteristic odor of said volatile substance to said articles, a rotary support for the spool, means opposing free rotation of the spool, and a handle device whereby the spool, together with the support, may be rotated thereby to dispense the articles constituting the roll.

3. In combination in a dispensing receptacle, a spool having a hollow elongate barrel and a head at each end of the barrel, the barrel having openings in its wall, one of the heads having a central aperture giving access to the interior of the barrel, a body of absorbent material within the barrel operative to hold a volatile odoriferous substance in such relation to a roll of connected dispensable articles wound on the barrel as to impart the characteristic odor of said volatile substance to said articles, a rotary support for the spool, pawl and ratchet means operative to prevent free rotation of the support, the support having means operable by engagement with the spool head to prevent rotation of the spool relative to the spool, and means whereby the spool may be turned thereby to facilitate the dispensing of the articles one-by-one from the roll.

4. In combination in a dispensing receptacle, a spool having a hollow elongate barrel and a head at each end of the barrel, the barrel having openings in its wall, one of the heads having a central aperture giving access to the interior of the barrel, a body of absorbent material within the barrel operative to hold a volatile odoriferous substance in such relation to a roll of connected dispensable articles wound on the barrel as to impart the characteristic odor of said volatile substance to said articles, a rotatable support for the spool, said support having an eccentrically located projection designed to enter an aperture in the spool head thereby to prevent relative rotation of the spool and support, detent means operative to prevent free rotation of the spool, a drive element engaging the opposite head of the spool, and means whereby the drive element may be turned.

5. In combination in a dispensing receptacle, a spool having a hollow elongate barrel and a head at each end of the barrel, the barrel having openings in its wall, one of the heads having a central aperture giving access to the interior of the bar-

rel, a body of absorbent material within the barrel operative to hold a volatile odoriferous substance in such relation to a roll of connected dispensable articles wound on the barrel as to impart the characteristic odor of said volatile substance to said articles, the spool heads having eccentrically located openings therein, a rotatable support for the spool, said support having projections engaging the openings in one head of the spool thereby to prevent relative rotation of the spool and support, a drive element having projections which engage the openings in the other head of the spool, and a handle whereby the drive element may be rotated thereby to turn the spool and support.

6. In combination in a dispensing receptacle, a base, a cylindrical shell having therein an elongate dispensing slot parallel to the axis of the spool, a rotatable support coaxial with the shell, detent means operative to prevent free rotation of the support, a spool having a hollow barrel and a head at each end of the barrel, the barrel having perforations in its wall and containing a body of odor-emitting material, the lower head of the spool resting upon the support, means operative to prevent relative rotation of the spool and support, a removable cover for the shell, said cover being rotatable relatively to the shell and having an external handle whereby it may be turned, and a drive element connected to the cover and within the upper part of the shell, the drive element having means engaging the upper head of the spool thereby to prevent relative rotation of the spool and drive element.

7. In combination in a dispensing receptacle, a hollow base having a bearing for a vertical shaft, detent means within the base operative to prevent free rotation of the shaft, a supporting disk fixed to the shaft above the base, said disk having upwardly projecting eccentrically located lugs, a cylindrical shell secured at one end to the base in coaxial relation to the shaft, a removable rotatable cover engaging the upper end of the shell, means for turning said cover, a drive disk secured to the cover, said disk being normally positioned within the upper part of the shell and having eccentrically located downwardly directed lugs, a spool having a barrel, and a head at each end of the barrel, one head of the spool resting on the rotatable support and having holes for the reception of the upwardly projecting lugs, the other spool head having holes with which the lugs of the drive disk engage, a shell having an elongate dispensing slot parallel to the axis of the shaft, and an annular shelf fixed to the barrel constituting a support for the lower end of a roll of connected articles to be dispensed, the slot in the shell being so located and of such dimensions as to constitute a guide for the articles as they emerge from the receptacle.

8. In combination in a dispensing receptacle, a base comprising a circular hollow upstanding boss having a central bearing opening, a shaft arranged to turn in said opening, a ratchet wheel secured to the lower end of the shaft within the base, a spring detent within the base engaging the ratchet and operative to prevent free rotation of the shaft, a supporting disk fixed to the upper end of the shaft, a cylindrical shell having its lower end telescoped over the boss and fixed to the base, a removable cover rotatably engaging the upper end of the shell, said cover having an external handle by which it may be turned, a drive disk fixed to the inner side of the cover, a spool having a barrel and a head at each end

of the barrel, one head resting on the supporting disk and the other head being adjacent to the drive disk, means operative to prevent relative rotation of the lower spool head and the supporting disk, and means operative to prevent relative rotation of the upper spool head and drive disk, the shell having an elongate dispensing slot parallel to the axis of the shaft, the material of the shell at one edge of said slot being so deflected as to constitute guide means for articles to be dispensed.

9. A match-dispensing receptacle comprising a core designed to receive a roll of attached but separable matches, the core being cylindrical and having an annular shelf intermediate its ends operative to support one end of the roll of matches, a housing of non-inflammable material, said housing having a narrow dispensing slot operative to permit withdrawal of the matches from the housing, said slot having an edge constituting means to assist in tearing the matches one-by-one from the roll.

10. In combination in a match-dispensing receptacle, a spool having an elongate barrel and a head at each end of the barrel, the spool being designed to hold a roll of connected matches, a rotatable support for the spool, said support having an eccentrically located projection designed to enter an aperture in the spool head thereby to prevent relative rotation of the spool and support, detent means operative to prevent free rotation of the support, a drive element engaging the opposite head of the spool, and means whereby the drive element may be turned.

11. In combination in a match-dispensing receptacle, a spool having an elongate barrel and a head at each end of the barrel, the spool being designed to receive a roll of connected matches, the spool heads having eccentrically located openings therein, a rotatable support for the spool, said support having a projection engaging an opening in one head of the spool thereby to prevent relative rotation of the spool and support, a drive element having a projection which engages an opening in the other head of the spool, and a handle whereby the drive element may be rotated thereby to turn the spool and support.

12. In combination in a match-dispensing receptacle, a base, a cylindrical shell having therein an elongate dispensing slot parallel to the axis of the spool, a rotatable support co-axial with the shell, detent means to prevent free rotation of the support, a spool having a barrel and a head at each end of the barrel, the spool being designed to receive a roll of connected matches, the lower head of the spool resting on the support, means operative to prevent relative rotation of the spool and support, a removable

able cover for the shell, said cover being rotatable relatively to the shell and having an external handle whereby it may be turned, and a drive element connected to the cover and within the upper part of the shell, the drive element having means engaging the upper head of the spool thereby to prevent relative rotation of the spool and drive element.

13. A match dispensing apparatus comprising a receptacle including a base, a side wall and a cover, and a rotatable core within the receptacle designed to receive a strip of attached but separable matches wound to form a roll, the core comprising means operative to impart a pleasing odor to the matches constituting said roll, and means for rotating the core thereby to unwind the roll of matches.

14. A match dispensing apparatus comprising a receptacle having a substantially cylindrical shell and a cover therefor and a pervious rigid, tubular, rotatable core within the receptacle designed to receive a strip of attached but separable matches wound to form a roll, a body of odor emitting substances within the core operative to impart a pleasing fragrance to the matches constituting the roll, and means for turning the core thereby to unwind the roll of matches.

15. A match dispensing apparatus comprising a receptacle having therein a rigid rotatable core designed to receive a roll of attached but separable matches, the core being hollow and of perforated material, a mass of absorbent material within the core containing a volatile odoriferous substance operative to impart a pleasing fragrance to the matches forming the roll, and means operative to prevent accidental rotation of the core.

16. A match dispensing apparatus comprising a receptacle, an elongate core within the receptacle for the reception of a strip of connected matches wound to form a roll, means supporting the core for rotation thereby to permit the roll of attached matches gradually to be unwound from the core as individual matches are dispensed, and means operative to facilitate the detachment of said matches as they are unwound from the roll.

17. In combination in a match dispensing receptacle a spool having an elongate barrel and a head at each end of the barrel, the spool being designed to hold a strip of connected matches wound to form a roll, a rotary support for the spool, means opposing free rotation of the spool, and a handle device whereby the spool together with its support may be rotated, thereby to dispense the matches constituting the roll.

DANIEL TOPJIAN.
